UNITED STATES PATENT OFFICE.

MORRIS FALKENAN, OF NEW YORK, N. Y., ASSIGNOR TO FALKENAN, OPPENHEIMER & CO., OF SAME PLACE.

EAR-RING.

SPECIFICATION forming part of Letters Patent No. 293,958, dated February 19, 1884.

Application filed October 25, 1883. (No model.)

To all whom it may concern:

Be it known that I, MORRIS FALKENAN, of the city, county, and State of New York, have invented certain new and useful Improvements 5 in Ear-Rings, of which the following is a specification.

This invention has reference to an improved construction of ear rings, by which the diamond or other precious stone is suspended 10 close to the lobe of the ear in a very reliable manner; and the invention consists of an ear-ring the ear-wire of which is widened at its front part and provided with an elongated slot, and with a transverse bridge extending 15 across the slot. The setting is suspended from the bridge by an eye, and permitted to swing freely in the slot of the ear-wire.

In the accompanying drawings, Figure 1 represents a side view of my improved ear-ring. Figs. 2 and 3 are respectively a side view and a front view of the ear-wire with the setting detached; and Fig. 4 shows a horizontal section of the ear-wire on line *xx*, Fig. 1.

Similar letters of reference indicate corresponding parts.

In the drawings, A represents the ear-wire of my improved ear-ring. The front part of the ear-wire A is widened, and provided with an elongated slot, *a*. A slightly-curved bridge, 30 *e'*, extends transversely across the slot *a*, and is securely attached to the ear-wire at both sides of the slot. The setting B, for the diamond or other stone, is suspended by an eye, *b*, from the bridge *a'*, the eye entering into the

slot and projecting partly above the ear-wire. 35 The setting B swings thereby freely on the bridge of the ear-wire, and is brought up close to the ear-wire, and thereby close to the lobe of the ear, according to the style prevailing at present. By thus suspending the 40 setting it can only swing forward or back, but very little sidewise, as it is confined by the side wires of the slot. The eye *b* is thereby less liable to become worn by the friction with the bridge, so that the setting and its diamond 45 are retained with greater security and durability without danger of getting detached by wear from the ear-wire.

Having thus described my invention, I claim as new and desire to secure by Letters Patent— 50

1. An ear-ring the ear-wire of which has an elongated slot at its upper front part and a transverse bridge that extends across the slot of the ear-wire, substantially as set forth.

2. The combination of an ear-wire having 55 a front part, with an elongated slot and a transverse bridge extending across the slotted part, with a setting suspended by an eye from the bridge of the ear-wire, substantially as set forth.

In testimony that I claim the foregoing as my invention I have signed my name in presence of two subscribing witnesses.

MORRIS FALKENAN.
